Inventor

United States Patent Office.

LEWIS C. ENGLAND, OF PHILADELPHIA, PENNSYLVANIA.

Letters Patent No. 96,212, dated October 26, 1869.

IMPROVEMENT IN TAN-BARK LEACHES.

The Schedule referred to in these Letters Patent and making part of the same.

To all whom it may concern:

Be it known that I, LEWIS C. ENGLAND, of the city and county of Philadelphia, and State of Pennsylvania, have invented a new and useful Improvement in Tan-Bark Leaches; and I do hereby declare that the following is a full, clear, and exact description of the construction and operation of the same, reference being had to the accompanying drawings, and to the letters of reference marked thereon.

The object of my invention consists in constructing leaches for extracting the tannin properties from bark, under downward hydraulic pressure, so that the liquor is collected evenly at the bottom of the leaches, by means of perforated tubes placed therein, and is conveyed upward, and distributed over the whole surface of each succeeding leach-vat through perforated tubes, placed across and near the top, thus allowing it to thoroughly commingle and pass through the bark, in every portion of each vat; consequently, I am enabled to extract the tannin from every particle of bark.

Heretofore, in the ordinary press-leach, where one tube, placed in the centre of the leaches, has been employed to convey the liquor from one vat to another, caused the liquor to pass in a current through the whole section of leaches, without being distributed evenly over and through the bark.

Figure 1 is a plan view of my improvement in tan-bark leaches, with the false bottom removed from one of the leaches.

Figure 2 is a sectional view of same on the line *a-b*.
Figure 3 is a sectional view of a portion of the top tube.

To enable those skilled in the art to make and use my invention, I will now proceed to describe its construction and operation.

The leach-vats *A*, *A¹*, *A²*, and *A³*, are of ordinary construction, and made perfectly water-tight.

In the bottom, and running transversely across each vat, is a series of tubes, *T*, *T¹*, *T²*, and *T³*, through the opposite sides of which is formed a series of perforations.

One end of each of the said tubes is made open, and the opposite ends connected to upright pipes *S*, *S¹*, *S²*, and *S³*, secured to the inner side of the leach-vats.

The upper ends of these tubes pass through and enter near the top of the adjacent leach-vat, and are made circular in form, where they pass through the side of the vat, and provided with adjustable plugs *P* and *P²*.

The tubes *C* and *C'*, which are placed across and near the top of each vat, are each perforated through opposite sides, and have one end closed, and supported by means of a notch cut on the outside of the tubes *S*, *S¹*, *S²*, and *S³*, and the opposite ends supported on

the circular ends of the upright tubes, which pass through from the adjacent vat, and fit into the bore of the tubes *C* and *C'*, so as to allow a free communication with them.

Passing around the outside of the section of leaches near the top, and connected with the vats *A* and *A³*, is a tube, *B*, the connection with it and the vat *A³* being through the upright tubes *S³*, and the communication with the vat *A* is made by means of the short pipes *D*.

The leach-vats are heated by means of steam passed through the coil or strands of pipes *E*, and the water introduced into each vat through the tube or hollow log *L* and the discharge-pipes *J*, *J¹*, *J²*, and *J³*, the communication between these pipes and the tube *L* being opened and closed by means of a tapering plug, *G*, inserted through an opening made in the top side of the tube *L*, this opening being closed by means of the plug *H*. When it is desired to remove the plug *G*, a hook is inserted through the opening in the tube *L*, and caught into a rod, secured across the centre of it, as shown in fig. 3.

The operation is as follows:

The openings in the pipes *D*, being closed by means of the plugs *P*, and those in the upright tubes *S*, by the plugs *P¹*, and the tubes *C* and *C'* placed in position in the vats *A²* and *A³*, water is then conveyed into each of the vats, partially filling them. A sufficient quantity of ground bark is then placed in the vat *A*, and more water introduced into this vat, until it is entirely full.

It is then allowed to stand the proper length of time, when the same quantity of ground bark is introduced in the vat *A¹*. The plugs *P¹* are then withdrawn, and the tubes *C* placed over the ends of the tubes *S*, and the plugs then inserted in the ends of the tubes *S¹*. The liquor which has passed down through the bark in the vat *A* will be collected evenly in the bottom of it, and will pass through the perforations in the tubes *T*, and up the side tubes *S*, and through the perforations in the tube *C*, and will be distributed evenly and thoroughly over the surface of the vat *A¹*.

The vat *A¹* is then supplied with more water, sufficient to fill the vats *A* and *A¹*. Fresh ground bark is then introduced into the vat *A²*. The plugs *P¹* are now withdrawn from the tubes *S¹*, and inserted in the tubes *S²*, and the tubes *C* placed over the ends of the tubes *S²*. The water from the vat *A¹* will now flow into the vat *A²*, through the perforated tubes *T²* and *C*, the water following from vat *A*, into which sufficient water is introduced to fill the three vats.

A sufficient quantity of fresh-ground bark is then introduced into vat *A³*, and the plugs *P¹* removed from

the tubes S^2 , and distributing-tubes placed on the ends of the tubes S^2 , and more fresh water added to vat A , so as to fill the whole section.

While this process of filling has been going on, the vats have all been heated by means of the steam-pipes E , and the condensed steam all discharged into the vat A ; through the hollow log or tube L and discharge-pipe J . The liquor in the vat A^3 , or last filled vat, is now as strong as it would be in a section of four leaches.

The liquor is now drawn from the bottom of the vat A^3 , in quantity equal to the amount that one leach would contain. The plugs P^1 are then placed in the upper ends of pipes S^1 , and the water or weak liquor in vat A pumped into the vat A^1 . The vats A^1 , A^2 , and A^3 are now all full again. The vat A , being cut off from the rest of the sections by means of the plugs P^1 , inserted in the tubes S , allows the spent bark to be removed, and the vat prepared for, and into which fresh bark is placed, and the plugs P withdrawn from the pipes D , and perforated tubes placed over the ends of these pipes, through which the liquor from vat A^3 , flowing around and through the tube B , passes, water is now added to vat A^1 , and the operation re-

peated. In practice, from four to ten leach-vats are used in a section:

When it is desired to make the liquor as strong as it can be made from fine-ground bark, (without evaporating,) a larger number of vats are used.

Having thus described my invention, its construction and operation,

What I claim, and desire to secure by Letters Patent of the United States, is—

1. The lower perforated tubes T , T^1 , &c., and upper perforated tubes C and C' , arranged and operating as herein specified.

2. The arrangement of the outside tube B , upright or side tubes S , S^1 , &c., connecting-pipes D , and plugs P and P^1 , as and for the purpose specified.

3. The arrangement of the steam-pipe E , placed in the bottom of the vats, and on top of the perforated tubes T , T^1 , &c., as and for the purpose specified.

In testimony whereof, I have hereunto signed my name, in the presence of two subscribing witnesses.

LEWIS C. ENGLAND.
